US0D1064080S

(12) **United States Design Patent** (10) Patent No.: **US D1,064,080 S**
(45) Date of Patent: ** Feb. 25, 2025

(54) **CONTROLLER**

- (71) Applicant: **META PLATFORMS TECHNOLOGIES, LLC**, Menlo Park, CA (US)
- (72) Inventors: **Yi-yaun Chen**, Seattle, WA (US); **Mauricio Romano**, Redmond, WA (US); **Peter Allan Chase Newbury**, Nice (FR); **Peter Wesley Bristol**, Seattle, WA (US)

- (73) Assignee: **META PLATFORMS TECHNOLOGIES, LLC**, Menlo Park, CA (US)

(**) Term: **15 Years**

(21) Appl. No.: **29/963,011**

(22) Filed: **Sep. 13, 2024**

Related U.S. Application Data

- (63) Continuation of application No. 29/858,899, filed on Nov. 4, 2022.

(57) **CLAIM**

The ornamental design for a controller as shown and described.

DESCRIPTION

FIG. 1 is a top, rear perspective view of a controller showing our new design;

FIG. 2 is a top front left perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The dash-dash broken lines depict portions of the controller that form no part of the claim. The dash-dot-dash broken lines are boundary lines that form no part of the claim. The stippling surface shadings form part of the claim.

1 Claim, 8 Drawing Sheets
